CAMOUFLAGE FABRICATING MACHINE

William E. Meyer, Detroit, Mich., assignor to
 Parker-Wolverine Company, Detroit, Mich., a
 corporation of Michigan

Application June 18, 1942, Serial No. 447,602

3 Claims. (Cl. 1-2)

The present invention relates to machines for fabricating camouflage, and particularly to machines for depositing and securing a fibrous material, such as steel wool, onto a wire mesh backing member.

One of the primary objects of the present invention is to provide a fabricating machine of the type mentioned by which camouflage may be quickly fabricated in large quantities.

Other objects of the invention will become apparent from the following specification, the drawings relating thereto, and the claims hereinafter set forth.

In the drawings, in which like numerals are used to designate like parts in the several views throughout;

Figure 1 is a broken side elevational view of a camouflage fabricating machine embodying features of the present invention;

Fig. 2 is a top plan view of the structure shown in Fig. 1;

Fig. 3 is a fragmentary, perspective view of a portion of the structure shown in Fig. 1 illustrating the stapling and feeding mechanism;

Fig. 4 is a cross-sectional view, taken substantially along the line 4-4 of Fig. 3;

Fig. 5 is a cross-sectional view taken substantially along the line 5-5 of Fig. 3; and

Fig. 6 is an enlarged fragmentary plan view of the camouflage formed by the apparatus of the present invention.

According to the present invention a fibrous material is superimposed on a wire mesh and is secured thereto. In the apparatus particularly illustrated, steel wool is the fibrous material employed, but it is to be understood that other fibrous materials may be used within the scope of the present invention. The wire mesh having the fibrous material secured thereto is coiled into rolls. Such rolls may then be bonderized and thereafter painted. In some instances the wire mesh and the steel wool are bonderized prior to the fabrication by the present machine. The present invention is particularly concerned with the machine for depositing and securing the steel wool to the wire mesh.

Referring to the drawings, an elongated table support is generally indicated at 10. A mounting frame, generally indicated at 12 is disposed adjacent one end of the table support 10. A roll of wire mesh 14 is rotatably mounted on a transverse shaft 16 which is supported in suitable bearings mounted on the frame 12 in the lower portion thereof. Such wire mesh in the embodi-

ment illustrated is in the form of ordinary chicken wire.

A plurality of other pivot shafts 18 are mounted to the frame 12 on suitable bearings or hangers secured thereto. Such shafts 18 are adapted to have pivotally mounted thereon a plurality of rolls 20 of strips of steel wool 22. Such rolls 20 are disposed on the several shafts 18 in such a fashion that when the strips 22 of steel wool are unwound therefrom such wool substantially covers the support 10 and the wire mesh 14 transversely thereof. As the strips 22 are unwound from the rolls 20 certain of them are disposed around guides 24 which are mounted on the frame 12 and which are so disposed that the strands 22 pass without interference with each other to and between feed rollers 26 and 28.

In being passed to the feed rollers 26 and 28 such strands 22 are guided and kept in proper transverse relationship by upwardly projecting guide fingers 30. Such guide fingers 30 are spaced from each other substantially the width of the strips 22 and receive the strips therebetween so that such strips form a substantially continuous sheet of steel wool transversely of the wire mesh in passing between the feed rolls. It will be appreciated that there are provided the same number of rolls 20 as there are spaces between the guide fingers 30, so that the steel wool forms the continuous sheet.

The upper feed roll 28 is an idler roller and is mounted for vertical adjustment within a suitable frame so that it may be adjusted toward and from the driven feed roller 26 so as to apply the proper feed pressure on the strips 22. The feed roller 26 is a driven roller and is mounted upon a drive shaft having a gear keyed thereto. The driving gear is driven through a suitable electric motor 32 which is operatively connected to a variable speed reducer 34. Such speed reducer 34 has a drive gear thereon which is connected to the drive gear for the roll 26 through a drive chain 36. It will thus be appreciated that the strips of steel wool 22 are fed toward the support 10 in superimposed relation to the wire mesh 14.

The wire mesh 14 is disposed on the table 10 and is moved therealong by a means to be described hereinafter. The strips 22 drop downwardly between the supporting frame 12 and the support 10 and are continuously fed to such space. The steel wool and the mesh 14 are intermittently moved along the table 10 and the sagging of the steel wool strips within the space permits such intermittent movement along the support. In

order to maintain proper tension in the strips 22 and to insure their lying against the wire mesh 14, a pipe or rod 38 is disposed in the trough of the sag in strips 22. It will be appreciated that such rod 38 rides in the trough as the strips are intermittently fed along the table 10.

The mesh 14 having the strips of steel wool 22 superimposed thereon are fed along the table 10 by means of a reciprocating clamp generally indicated at 40. Such reciprocating feed clamp 40 is best shown in Figures 4 and 5. The feed 40 comprises a reciprocating frame having side members 42 connected together by transverse members 44 and 46. The members 44 and 46 are disposed above the table 10 and rollers 48 are pivotally mounted to the side members 42 and are adapted to roll along trackways 50 mounted on the table 10 longitudinally thereof.

The reciprocating frame 42 carries a clamp which includes the transverse member 46 forming the underside of the clamp, and an upper transverse member 52. The member 46 has a pair of transversely extending, continuous projections 54 formed on the upper surface thereof, and the upper member 52 has three depending similar projections 56 formed thereon. Projections 54 and 56 are so disposed with respect to each other that the projections 54 are adapted to be received between the adjacent projections 56. When the members 46 and 52 are in clamping position the projections assume the position shown in Fig. 5 so that the strips 22 and mesh 14 are clamped therebetween with such firmness that the strips and mesh may be moved along the table 10 as the carriage is moved in one direction. The edges of the projections 54 and 56 are round and such projections are continuous so that they do not catch on the wire mesh or the steel wool as the clamping elements are moved with respect thereto.

The upper member 52 has a transverse member 58 secured to the top surface thereof, and such members 52 and 58 are secured at their ends to pivot arms 60. Such pivot arms 60 are disposed at the sides of the table 10 and are pivotally connected to the side members 42 of the reciprocating frame through upstanding brackets 62 and pivot pins 64.

The leading ends of the arms 60 are so shaped that they lie substantially horizontal when the members 46 and 52 are in their clamping position. The arms 60 are pivoted about the pivot pins 64 in order to move the members 46 and 52 to clamping and releasing positions by means of an air cylinder 66. Such air cylinder 66 is mounted to a frame having side members 68 connected by a transverse member 70. The side members 68 are secured to the side members 42 of the reciprocating carriage so that the mounting frame for the cylinder 66 reciprocates with such carriage. The upper end of the air cylinder 66 is pivotally connected to the member 70 substantially midway between the ends thereof by means of a pivot pin 72. A piston rod 74 projects through the cap end of the cylinder 66 and is pivotally connected to a mounting plate 76, which is secured to the members 52 and 58 substantially midway between the ends thereof. Air ports are provided in the upper and lower ends of the cylinder 66 on opposite sides of the piston, in the usual way, for reciprocating the piston rod 74 to raise and lower the clamping member 52.

An air conduit 78 communicates with the lower port, and an air conduit 80 communicates

with the upper air port. Such conduits 78 are mounted to one of the frame members 68 and have flexible conduits 82 and 84 connected thereto through suitable connectors.

The conduits 82 and 84 communicate with the opposite ends of a conventional air reversing valve 86, which is mounted upon a frame member 88 of the table 10 under the reciprocating feed carriage. An inlet port is provided in the valve 86 in the usual way, and an air conduit 90 communicates with such inlet port and also communicates with a suitable source of air pressure (not shown). The valve is reversed by an upstanding finger or lever 92, which is disposed in the path of a pair of depending reversing fingers 94 and 96, which are mounted on one of the side members 42 of the reciprocating feed carriage.

It will thus be appreciated that as the feed carriage moves in one direction, the finger 94 shifts the valve through the operating arm 92 to admit air under pressure to the conduit 82. When air under pressure enters conduit 82, it passes through the lower port in cylinder 66 to raise the piston rod 74 and to move the clamping member 52 to its releasing position. When the carriage moves in the opposite direction, the finger 96 engages the member 92 to shift the valve to admit fluid under pressure to the conduit 84, which passes into the upper port in cylinder 66 to move the clamp downwardly to its clamping position.

The feed carriage is reciprocated through connecting arms 101 disposed adjacent the side frame members 42 and pivotally connected thereto by means of pivot pins 102. The opposite ends of such arms are pivotally connected to a crank arm 104 through pivot pins 106. The crank arms 104 are keyed to a transverse shaft 108, which is mounted within suitable bearings on the frame member 88. A drive gear 110 is geared to such shaft 108. The drive gear 110 is driven by a suitable electric motor 112 through a variable speed reducer 114, having a drive gear 116 associated therewith. Such drive gear 116 drives the gear 110 through a chain drive 118.

It will thus be appreciated that as the gear 110 is driven, the crank arms 104 are caused to rotate and, through the connecting arms 101, the carriage is caused to reciprocate. The fingers 94 and 96 are, of course, positioned on the reciprocating frame, so that they engage the shifting lever 92 at the ends of the stroke of the feed carriage. When the reciprocating carriage reaches the end of the stroke, to the left, viewing Figure 4, the clamp 52 is moved downwardly to its clamping position. The carriage then moves toward the right, viewing Figure 4, to pull the mesh 14 and strips 22 therealong. When the carriage reaches the end of its stroke in that direction, the valve 86 is reversed to move the clamp 52 upwardly to its releasing position. The carriage is then returned to the left, with the clamp 52 in such releasing position, until it reaches the end of its stroke in that direction, when the cycle is repeated.

Prior to the engagement of the mesh and steel wool strips by the reciprocating feed clamp, the steel wool is secured to the wire mesh transversely thereof. Such securing means is generally indicated at 120, and includes a framework comprising upstanding members 122 having cross members 124 secured thereto above the table 10. The securing means includes a plurality of conventional stapling mechanisms 126 having the

usual feed magazine pivoted adjacent the rear end onto a cross-plate 128, which extends transversely of the table and is mounted to frame members in spaced relation to the upper surface of the table so that the steel wool passes thereunder. The stapling members handle the usual U-shaped staples which are fed out of the leading ends of the pivoted arms of the stapling mechanism so that as such arms strike the transverse die 130 the staples are emitted from the magazines and clamped around the steel wool and the strands of the mesh 14.

A rounded rod, or pipe, 132 is fixed to the top of the table 10 adjacent the die 130, so that the material being stapled passes thereover without catching. The pivoted arms 126 of the stapling mechanisms are connected in groups to transverse bars 134. Such bars 134 are connected to the depending piston rods 136 of air cylinders 138. The connections between the bars 134 and the arms 126 are such that the arms 126 are first moved downwardly into engagement with the bars 130; and then further downward movement of the bars 134 emits the stapling clips and clamps them about the steel wool and the wire mesh. This is the usual operation of the conventional stapling mechanisms.

The cylinders 138 have the usual air ports on opposite sides of the piston, and are provided with the usual conduits leading to a common reversing valve. Such valve may be similar to the valve 86, and has an air pressure port leading to a suitable source of air pressure. The operating lever for the valve in the embodiment illustrated is hand operated, and such valve is operated to effect the stapling operation at the time that the clamp of the feed carriage is in its releasing position, so that the wire mesh is stationary on the table. The steel wool is thus clamped at spaced intervals thereacross to the wire mesh prior to its engagement by the reciprocating feed clamp.

After the mesh and steel wool leave the feed carriage, the steel wool and wire mesh are further secured together by hand by transversely extending wires 140. Such wires 140 are applied by a longitudinally curved, transversely flat needle 142. The wires 140 are of predetermined length, corresponding to the width of the camouflage strip, and one end of each of the wires is attached to a needle 142. By moving the needle transversely of the camouflage and moving the point up and down, the wire will be threaded above the steel wool and under the wire mesh, as best shown in Figure 6. The ends of the wire are then twisted about the edges of the wire mesh, so that such wires are held in position. The wires, of course, may be applied at suitable intervals along the camouflage.

The camouflage, consisting of the mesh 14 with the steel wool secured thereto, leaves the table 10 and is received by a coiling mechanism, generally indicated at 144. Such coiling mechanism 144 includes a mounting frame adapted to have a coiling shaft 146 removably mounted thereon. The camouflage is received on the coiling means by the guide bars 148, and the leading end thereof may be wrapped around the shaft 146. The shaft 146 is, of course, rotated to coil a predetermined amount of camouflage thereon, and during the period of rotation the camouflage is continuously wound. However, it is intermittently fed to the coiling mechanism and the camouflage sags in the space between the table 10 and the coiling frame.

The shaft 146, when it is positioned on the frame, is operatively connected to a drive gear, which is driven by an electric motor 150 through a variable speed reducer 152 and through a chain drive 154.

In order to control the coil on the shaft 146, in accordance with the feed to the coiling machine, a rod or pipe 156 is disposed in the trough of the sagging portion of the camouflage between table 10 and the coiling mechanism 144. As the camouflage is intermittently fed to the space, the trough will, of course, move up and down.

The rod 156 serves to keep the camouflage in a proper taut condition and also to control the operation of the motor 150. To control such operation, a pair of pivot arms 158 are pivotally connected to the rod 156 at opposite ends thereof; and the opposite ends of the arm 158 are pivotally connected by pivot pins 160 to depending brackets secured to the coiling frame.

A conventional mercury switch 162 is fixed to one of the arms 158 and is connected to the motor 150 through suitable electric lines 164. The switch 162 is of such a construction that the rod 156 moves upwardly and pivots the arms 158 upwardly; and when the arms reach a predetermined position, the switch 162 is tilted to cut off the motor 150. When the intermittent feed is such that the camouflage sags downwardly to a predetermined point, the arms 158 drop downwardly and the switch 162 is tilted to make the circuit and operate the motor 150 to cause rotation of the shaft 146 to coil the camouflage. When a predetermined amount of camouflage has been coiled, the camouflage is cut transversely thereof, by scissors, in the space between the guide rods 148 and the coiling shaft 146.

Suitable flattening or ironing rolls may be disposed on top of the camouflage at suitable places along the table, so as to iron it out as it passes along the table. For example, one of such ironing bars is shown at 170 prior to the entrance of the camouflage material to the stapling mechanism 120. Thus, the camouflage passes between the bar 170 and the table 10, and such bar serves to flatten or smooth out the steel wool prior to the stapling operation.

What is claimed is:

1. In a machine for fabricating camouflage, an elongated support, rotatable means mounting a roll of wire mesh adjacent one end of said support, means mounting a plurality of individual rolls of fibrous material above said first-named means and transversely spaced across said support, spaced guide fingers disposed transversely of said support between which the fibrous material from the individual rolls passes to distribute the fibrous material transversely of said wire mesh, means disposing said mesh and fibrous material on said elongated support with said fibrous material superimposed on said mesh, means for securing said fibrous material to said mesh, means for moving said fibrous material and mesh along said elongated support, and coiling means for receiving and coiling said fibrous material and said mesh.
2. In a machine for fabricating camouflage, an elongated support, means rotatably mounting a roll of wire mesh adjacent one end of said support, means mounting a plurality of individual rolls of fibrous material above said first-named means, said rolls of fibrous material being spaced transversely of said support so that said wire mesh is substantially covered by said fibrous material, spaced guide fingers disposed transversely of said

support between which the fibrous material from the individual rolls passes, means disposing said mesh and said fibrous material on said elongated support with said fibrous material superimposed on said mesh, stapling means for stapling said fibrous material to said mesh, said disposing means comprising a reciprocating clamp disposed transversely of said elongated support and adapted to clamp said fibrous material and mesh transversely thereof and to move said fibrous material and said mesh along said elongated support, and coiling means for receiving and coiling said fibrous material and mesh.

3. In a machine for fabricating camouflage, an elongated support, means for rotatably mounting a roll of wire mesh adjacent one end of said sup-

port, means mounting a supply of fibrous material above said first-named means and transversely of said support, means disposing said mesh and fibrous material on said elongated support with said fibrous material superimposed on said mesh, means for securing said fibrous material to said mesh, said disposing means comprising a pair of superimposed and transverse clamping plates for clamping said fibrous material and said mesh and for moving said fibrous material and said mesh along said elongated support, the facing surfaces of said plates having complementary grooves and recesses formed therein, and coiling means for receiving and coiling said fibrous material and said mesh.

15 WILLIAM E. MEYER.
